[57] **CLAIM**

The ornamental design for a storage container handle, as shown and described.

DESCRIPTION

FIG. 1 is an orthographic projection view of a storage container handle showing our new design, the broken line showing of the storage container being for illustrative purposes only and forming no part of the claimed design;

FIG. 2 is a front elevation view thereof;

FIG. 3 is a right side elevation view thereof, the left side elevation view being a mirror image thereof;

FIG. 4 is a top plan view thereof;

FIG. 5 is a rear elevation view thereof; and,

FIG. 6 is a bottom plan view thereof.
